MACHINE FOR MAKING HOLLOW BLOCKS

Allen Kissam, Orlando, Fla.

Application August 6, 1938, Serial No. 223,533

13 Claims.

(Cl. 25—41)

This invention relates to machines for making hollow blocks of cementitious mixtures or the like, and more particularly to an improved apparatus for properly and adequately tamping the mixture in a minimum space of time and with a high degree of efficiency.

A general object of the invention is to provide a machine of the vertical stripper type including an oscillating core which not only tamps or compacts the material against the side walls of the mold box but also against the end walls, or in the case of a machine employing multiple cores, to compact the material against the side and end walls, as well as between the cores.

Accordingly, the present invention provides a block making machine including a rectangular core mounted on a vertical axis for angular movement relative to the walls of the mold box, the core being positioned vertically, that is, parallel to the path of movement of the stripper means so that after its angular movement ceases the stripping may be readily accomplished. In that connection the invention contemplates a core mounted for angular movement which not only always maintains its generally vertical position, but also stops with its side walls so positioned as to offer the least resistance to the removal of the pallet, and which, because of its relatively short radius of angular movement has less inertia and therefore requires less power to operate. Moreover, due to the fact that the core is vertically mounted and moves on a vertical axis, and, therefore, has a relative twisting movement to effect tamping it is possible to make deeper mold boxes. That is to say, the height or depth of the mold box, as well as the core, may be considerably increased with the present invention, since the axis of angular movement is parallel to the walls of the mold box and also parallel to the stripper means in the mold box.

A further object of the invention is to provide an oscillating core including means located adjacent the pallet of the stripper means when in tamping position, to not only permit movement of the mold relative to the pallet while providing a seal between the core and the pallet to prevent leakage of material at this point but, at the same time, prevent abrasive contact between the core and the pallet. Preferably, this means is in the form of a renewable insert or gasket of rubber or other displaceable material which will give or yield and thus avoid the abrasive effect incident to rapid operation of the parts, thereby increasing the operating life of the

core, and at the same time reducing noise in operation.

Another object of the invention is to provide means for mounting the core for angular movement in the mold which is effectively housed and protected against the entry of sand or other foreign matter into the parts which support the mold, thereby shielding them and consequently adding to their longevity and efficiency.

A still further object of the invention is to provide a strong and rugged construction which will stand up under all operating conditions, and whose parts may be readily made to facilitate machining operations where necessary, and which parts are so assembled as to permit of readily making replacements or repairs.

With the above and other objects in view which will more readily appear as the nature of the invention is better understood, the same consists in the novel construction, combination and arrangement of parts hereinafter more fully described, illustrated and claimed.

In the accompanying drawings:

Figure 1 is a vertical sectional view of the improved apparatus.

Figure 2 is a vertical sectional view taken on the line 2—2 of Fig. 1.

Figure 3 is a top plan view of the mold box, and oscillating cores therein.

Figure 4 is a transverse sectional view on the line 4—4 of Fig. 1.

Figure 5 is an enlarged detail vertical sectional view of the pivotal mounting for the cores.

Figure 6 is a detail section taken on the line 6—6 of Fig. 4.

Figure 7 is a detail perspective view of one of the cores and a portion of its pivotal mounting.

Similar reference characters designate corresponding parts throughout the several figures of the drawings.

According to the embodiment of the invention shown in the drawings, the framework of the machine is designated generally as A, the mold box as B, the said mold box having therein the vertically movable stripper means designated generally as C and including the pallet C'. The stripper means and pallet surround the oscillating cores D which are actuated by suitable power-driven means generally identified as E. The top of the frame, above the mold box B is provided with a sliding hopper F which may be shifted from a position over the mold box B as shown in Fig. 1 to a rearward position over

the apron F' when it is desired to strip the block from the mold.

The mold box B includes side and end walls and the stripper means C including the pallet C' are mounted on suitable standards C² slideable in the frame A and connected by a cross bar and roller element C³ adapted to be engaged by the levers C⁴ carried by a rock shaft C⁵ journaled in the frame and controlled by an operator's lever C⁶.

The apparatus shown in the drawings is intended to make a hollow block having a plurality of openings therein and therefore two oscillating cores D are shown. However, since these cores and their mounting means as well as their operating connections are the same, a description of one will suffice for the other. It will of course be understood that the invention is the same if only a single core is used in the mold box.

Each of the cores D is preferably of rectangular cross-section and normally has its side and end walls parallel respectively to the side and end walls of the mold box. Suitable mounting means is provided for each core to permit it to oscillate on its vertical axis so that the side walls of the core may exert a tamping force toward the side and end walls of the mold box. In addition the core itself is of novel construction in the respect that it is provided adjacent the pallet with a yielding face.

As will be observed from Figures 1 and 7 the hollow rectangular core D is preferably provided at its lower face with a plate or shim portion 1 of smaller dimensions than the bottom of the core, the said plate cooperating with a flange 2 or its equivalent to provide therebetween a space for receiving a non-metallic insert or gasket 4. The said insert or gasket 4 is preferably of rubber or other displaceable material which will yield when the core moves relative to the pallet thereby to avoid abrasive wear between the pallet and the core and at the same time substantially seal the space or clearance between the core and the pallet. The plate 1 and flange 2 are held in assembled relation to the bottom of the core by the bolts or other fastenings 5 so that when the insert 4 is positioned between them it may be compressed to cause the material thereof to slightly extend or bulge beyond the outer faces of the core and flange 2. While, as previously indicated, the insert or gasket 4 is made of rubber, it will of course be understood that any other suitable and equivalent means, such as felt or the like, may be used, but owing to the circumstances under which the insert is used it is desirable to have some material which is not only yieldable or displaceable but also waterproof and capable of standing up under deformation or displacement.

The flange 2 is preferably a part of the mounting means for the core which includes the tubular member 6 which forms a part of the vertical pivot means for the core and serves to completely shield and house a vertical pivot shaft 7 therein. This pivot shaft is non-rotatably mounted at its lower end in suitable brackets 8 secured to the bottom of the mold box as indicated at 9. The inner bore of the tubular member 6 is provided with shoulders 6^a and 6^b which serve as opposite abutments against which suitable roller bearing units 10 may be positioned. These roller bearing units rotatably mount the tubular member 6 on the shaft 7, and as will be observed from Figure 5 the upper end of the shaft is reduced in diameter as indicated at 7^a

to provide a shoulder for the inner member of the upper bearing race 10, and is further reduced and threaded to receive a nut 7^b for clamping the inner race to the shaft. Due to the fact that the plate 1 is bolted to the flange 2, it will of course be understood that the nut 7^b is accessible for the purpose of assembling the tubular member relative to the shaft 7 before the plate 1 and core D are applied. The space between the lower end of the tubular member 6 and the shaft 7 is preferably provided with a felt or equivalent washer 11 while the lower end of the tubular member is provided with a packing or gland nut 12 so that grease packed in the space between the shaft and the tubular member between the roller bearing units 10-10 will be prevented from leaking out the bottom of the tubular member. The lower end of the shaft 7 may be keyed in any suitable manner to the bracket 8. Preferably, however, the arrangement is such that the shaft may be disconnected from the bracket by upward movement to permit the entire core unit to be lifted out of the bracket and mold box.

The lower end of the tubular member 6 is provided with a substantially tangential portion 6^c which forms an attaching base for one end of an operating lever 13 which extends horizontally to the rear of the machine to be connected with a source of power for oscillating the tubular member and consequently the core D on the vertical pivot axis provided by the shaft 7. Since two core units are shown in the present machine it will of course be understood that each core unit has an operating lever 13, each spaced laterally from the other, as will be apparent from Figure 4.

A suitable source of power, for example, an electric motor M is mounted on suitable suspending means M² carried by the rear of the frame A. This motor is provided with a shaft 14 extending substantially parallel to and between the levers 13. A pair of eccentrics 15 are suitably spaced along the shaft 14 and preferably have therebetween another eccentric 16. The pair of eccentrics 15 are connected by a bifurcated link 15^a with a ball and socket joint 15^b associated with the free end of one of the levers 13. Also, the eccentric 16 is connected by a link 16^a with a ball and socket joint 16^b associated with the end of the other lever 13. The purpose of this arrangement of eccentrics is to preferably distribute the load incident to the operation of the cores on the motor-driven shaft 14. It will of course be understood that the eccentrics 15-15 and 16 are arranged 180° out of phase so that the levers 13-13 will be moved toward and away from each other in operation as indicated by the dotted lines in Fig. 4.

From the foregoing it will be apparent that when the motor M is in operation the respective core units D will be oscillated about the vertical pivot axis 7, thereby to tamp the material in the mold. The degree of angular movement of the core units within the mold is comparatively small. In other words, the oscillation of the core units takes place about a relatively small radius. Owing to the rapid oscillation of the core units, however, the material in the mold will be quickly and positively tamped against the walls of the mold box. While sufficient clearance is provided between the sides of the core and the pallet to permit the stripper means, including the pallet, to clear the cores when ejecting the completed block, nevertheless, it is desirable to stop the

cores when the block is finished in a position where the side walls thereof will offer the least resistance to the operation of the stripper means. In other words, it is desirable to insure the stopping of the cores so that their sides are parallel to the sides of the pallet.

One means of accomplishing the above result is shown in Figures 1 and 4 of the drawings. The shaft 14 is preferably journaled in suitable hangers 17 and 18 suspended from the frame A, and between the hangers is provided with the crank portions 19 and 20 having an angular relation of 180° to each other and preferably having an angular relation of 90° to the eccentrics 15 and 16. Each crank portion is provided with a sleeve 19a and 20a which is connected with a coil spring 21 and 22 respectively, the said spring 21 being anchored as at 21a to a portion of the frame A and the spring 22 being anchored at its lower end to a bracket 22a carried by the base of the machine. These springs, during the operation of the shaft 14 will be alternately stretched as their respective cranks move, and when the power to the motor is cut off the tension in the springs will tend to bring the shaft 14 to a position to rest which will bring the eccentrics for operating the levers 13 to a position which will permit the cores to cause their side faces to align with each other and also align with the opening in the pallet which surrounds the cores. Thus, when the stripper means, including the pallet is moved vertically in the mold box the cores will offer a minimum resistance to the stripping or ejection of the completed block from the mold.

In operation the measured charge for the block to be formed is shifted by the hopper from a position over the apron F' to a position over the mold so that the charge will fall into the mold box and about the cores D. The operator then closes a switch to the motor and the cores are caused to oscillate on their vertical pivot axes in accordance with the construction described. Due to the presence of the soft or displaceable face of the core adjacent the pallet, it will be apparent that angular movement of the core can take place while at the same time substantially sealing the space between the pallet and the core. When the motor has been in operation a sufficient length of time to properly tamp the concrete, usually about ten seconds, the current to the motor is cut off and the cores come to rest in a position to permit the stripping of the block from the mold to be effected. This is accomplished by the operator moving the lever C⁶ which moves the stripper means, including the pallet, upwardly through the lever arms C⁴, roller C³ and uprights C². When the block is removed from the mold box on the pallet another pallet is placed into position and the operation described repeated.

The novel construction of the core units D permits of readily renewing the insert or gasket 4 when desired, although it will of course be understood that due to the displaceable characteristic of this insert, the life of the core unit is materially increased so that renewals will only be infrequently required. Moreover, due to the yielding or displaceable characteristic of the insert 4 noise incident to the operation of the core within the pallet is materially reduced. Also, because of the novel manner in which the vertical pivot mounting for the core is arranged it is possible to employ a ball or roller bearing mounting which may be packed with grease for efficient operation and which is completely housed and shielded from foreign material.

I claim:

1. In a machine for making hollow blocks, the combination with a mold box and vertically operating stripper means therein, of a rectangular core within the mold box and mounted on a vertical pivot for oscillation relative to the side and end walls of the said mold box, and means for oscillating the core.

2. In a machine for making hollow blocks, the combination with a mold box and vertically operating stripper means therein, of a rectangular core within the mold box and mounted on a vertical pivot for oscillation relative to the side and end walls of the mold, means for oscillating the core, and means for stopping the core with its side walls in a position to offer the least resistance to the movement of the stripper means.

3. A machine for making hollow blocks, including, in combination, a mold box, vertically movable stripper means operable in the mold box, a core of rectangular cross-section within the mold box and having substantially vertical walls parallel with the walls of the mold box, vertical pivot means for permitting the core to oscillate in a plane transversely of the mold box, and means for oscillating said core on said pivot means.

4. A machine for making hollow blocks, including, in combination, a mold box, vertically movable stripper means operable in the mold box, a core of rectangular cross-section having substantially vertical walls parallel with the walls of the mold box, vertical pivot means for permitting the core to oscillate in a plane transversely of the mold box, lever means connected to a part of said vertical pivot means, a motor, a shaft driven by said motor, connections between said shaft and said lever arm, and means connected to said shaft for stopping said core with its side walls parallel to the walls of the mold box and stripper means.

5. A machine for making hollow blocks, including, in combination, a mold box, vertically movable stripper means operable in the mold box, a core of angular cross-section in the mold box, pivot means for the core including a vertical shaft, a support for the core including a tubular portion telescopically fitting over said shaft, a lever arm connected to said tubular support, and means for imparting horizontal oscillating movement to said lever arm.

6. A machine for making hollow blocks, including, in combination, a mold box, vertically movable stripper means operable in the mold box, a core of rectangular cross-section in the mold box, pivot means for the core including a vertical shaft, a support for the core including a tubular portion telescopically fitting over said shaft, a lever arm connected to said tubular support, a motor-driven shaft disposed substantially parallel to and between said lever arms, eccentrics carried by said last named shaft, and links having their inner ends connected to said eccentrics and their outer ends connected to said lever arms.

7. A machine for making hollow blocks, including, in combination, a mold box, vertically movable stripper means operable in the mold box, a core of rectangular cross-section in the mold box, pivot means for the core including a vertical shaft, a support for the core including a tubular portion telescopically fitting over said shaft, a lever arm connected to said tubular support, a motor-driven shaft disposed substantially parallel to and between said lever arms, cranks formed on said shaft, eccentrics carried by said shaft,

3 links having their inner ends connected to said eccentrics and their outer ends connected to said lever arms, sleeves on said cranks, and springs connected to said sleeves tending always to pull the shaft to a position of rest whereby the core will be positioned to permit the stripper means to clear the same.

8. A machine for making hollow blocks, including, in combination, a mold box, vertically 10 movable stripper means operable in the mold box, a core of angular cross-section in the mold box, pivot means for the core including a vertical shaft, means for supporting the core on the shaft and protecting the said shaft from foreign material, and means for oscillating said last named means.

9. A machine for making hollow blocks, including, in combination, a mold box, vertically movable stripper means operable in the mold 20 box, a core of angular cross-section in the mold box, pivoted means for the core including a vertical shaft, roller bearings fitted to said shaft, a support for the core including a tubular portion surrounding and housing said shaft against foreign material and also engaging said roller bearings, and means for imparting an oscillating movement to said support.

10. A machine for making hollow blocks, including, in combination, a mold box, stripper 25 means including a pallet vertically movable in the mold box, a core positioned within the stripper means, means for mounting the core to oscillate in a horizontal plane relative to the pallet and mold box, and yielding non-metallic means on the core in the zone of the pallet to seal the core relative to the pallet, reduce wear and silence the operation of the core relative to said pallet.

11. A concrete block machine, including, in combination, a stationary vertical mold box, vertical cores of substantially rectangular cross section mounted permanently within the mold box on vertical axes, lever arms connected to said cores near their lower ends, a driven shaft, eccentrics on said shaft, link means connecting said lever arms to the eccentrics thereby to impart an oscillating motion to the cores about their

vertical axes, vertically movable stripper means operable in the mold box, a pallet mounted on said stripper means, and a hopper on top of said mold box and mounted to slide clear of the mold box to permit the block to be stripped therefrom, said hopper when positioned over the mold box serving to guide material into said mold box, and at the same time to hold an excess of material whose weight assists in packing said material in the mold box while the cores are oscillating rapidly therein. 10

12. A concrete block machine, including, in combination, a vertical stationary mold box, vertical rectangular cores mounted on vertical axes permanently within the mold box, vertically 15 operating stripper means, a pallet mounted on said stripper means within the mold box, a hopper slidably mounted on the top of the mold box, lever arms having their inner ends attached to the lower ends of said cores, and means connected with the outer ends of the said lever arms for imparting movement thereto for oscillating said cores on their vertical axes, said means including links connected to a motor driven eccentric shaft, said motor, shaft, links, and arms 20 imparting to the cores an oscillating motion in a horizontal plane at a speed sufficient to vibrate as well as pack the material between the cores and the walls of the mold box.

13. A concrete block machine, including, in combination, a stationary vertical mold box, vertically operating stripper means in the mold box including a pallet, vertical cores of substantially rectangular cross section in the mold box, a rubber insert in the cores at pallet line when the latter is in tamping position, said cores mounted 35 permanently within the mold box on vertical axes, lever arms connected to said cores near their lower ends, a driven shaft, eccentrics on said shaft, link means connecting said lever arms 40 to the eccentrics thereby to impart an oscillating motion to the cores about their vertical axes, and a hopper slidably mounted on top of said mold box to slide clear of the mold box when the block is to be stripped therefrom. 45

ALLEN KISSAM.
